United States Patent Office.

SYDNEY S. DURFEE, OF CHICAGO, ILLINOIS, ASSIGNOR TO HIMSELF AND
CHARLES A. GREGORY, OF SAME PLACE.

Letters Patent No. 60,864, dated January 1, 1867.

IMPROVED METHOD OF REMOVING BARS FROM RIVERS AND HARBORS.

The Schedule referred to in these Letters Patent and making part of the same.

Be it known that I, SYDNEY S. DURFEE, of Chicago, county of Cook, and State of Illinois, have invented a new and improved Mode of Removing Sand Bars from the beds of Rivers, the mouths of Ports and Harbors, and other similar places; and I do hereby declare that the following is a full and exact description thereof, reference being had to the accompanying drawings, forming a part of this specification.

The nature of my invention consists in placing obstructions or agitators at the bottoms of rivers, or in the entrances of ports and harbors, and other places of like character, where there are bars of sand or gravel to be removed, whereby the action of the current or undertow is made to wear and wash away the bar, and thus deepen the channel.

To enable others skilled in the art to make and use my invention, I proceed to describe its construction and operation.

I take a chain of the proper size and strength, that is to say, from one-half to three-quarters of an inch, and long enough to extend quite across the bar I desire to remove, and attach to this chain at proper intervals, or at about twenty feet apart, which I think near enough to effect the purpose, a number of wooden blocks, from fifteen to twenty-four inches in height, and from ten to fifteen inches in width, and of the form represented in the drawing, Figure A, or nearly resembling a tunnel, such as is in common use for pouring liquids into a bottle, or of the form shown in Figures C D. This attachment may be made by means of rings set at proper intervals in said chain, and inserting the necks of the blocks into the rings, where they can be then secured by bolts or screws, or may be made in any other suitable way. At each end of the chain I attach, by way of anchor, a piece of iron, shaped as in the drawings, Figure B, or very much like the upper shell of a tortoise, convex above and concave below, and with a hole or hook, or any other convenient attachment for the chain, about half way between the apex of the anchor and the edge thereof. Or the anchor may be of any other suitable shape, so as not to be easily moved by the current, and of a size and weight sufficient to keep the chain fixed in one place, or nearly so, and varying somewhat according to the length of the chain, the force of the current, and other attendant circumstances. No exact rule as to weight can be given, but for all ordinary use I think four or five hundred pounds would be sufficient. If the chain is very long, one or more additional anchors may be employed, if required, in the middle of the chain or at convenient intervals. For all ordinary bars, however, an anchor at each end will sufficiently answer the purpose. The chain thus prepared, with its blocks and anchors attached, is then to be sunk across the bar in the direction of the current at the place where it is required to create a channel or to deepen one already existing. Other chains of equal length and prepared in the same manner are next placed across the bar parallel to the first, and at a distance from each other varying, according to circumstances, from twenty to fifty feet. The distance is not important provided the chains are near enough to each other thoroughly to do the work. For all ordinary bars I think fifty feet to be the proper distance; if the bar is of a heavier and more compact character the chains may require to be placed a little nearer. The number of chains will, of course, depend upon the width of channel required, but partly, also, on the height of the bar, the force of the current, and other circumstances. In ordinary cases a single chain will open a channel of about fifty feet in width at the top, and considerably less than that at the bottom. Five chains, then, would open a channel about two hundred and fifty feet at the top, which would be as wide as is usually required. If the bar is very compact and heavy, or if the current or undertow is feeble, the chains would need to be nearer together than where the bar is light or the current strong. No particular rule can be given here, and none is needed, since whether the chains are placed at thirty, forty, or fifty feet apart, the effect will be very much the same, only where they are nearer together the work may be done somewhat sooner.

The manner in which this invention operates is as follows: Wherever a bar is formed in the bed of a river, it will be found that the current, though rapid, is smooth and unbroken; hence it glides smoothly over the bar without impinging against it or cutting into it. But if, now, any obstruction is placed in the bed of the river, the current is at once broken and deflected from its straight course. If the obstruction is of the right shape, and, to a certain extent, if of almost any shape, the current is made to impinge against the bottom, to cut into it, and necessarily, therefore, to cut it away and wash it away. If these obstructions are placed near enough together, and in a right line, the effect will be to cut a channel more or less deep as far as the obstructions extend. Thus, in the particular method described above, a channel will be cut for the whole length of the chain; the sand or mud will be cut

into, loosened, and washed away. The chain, with its blocks attached, will continually settle lower and lower, sand will be washed in towards the chain from both sides and then washed away, until at last a sufficient depth of water is obtained, when the chain may be taken up and used elsewhere. In this way the current of the river is made to perform the whole work of cutting away the bar; no dredging is required, and no other expense except the comparatively trifling cost of the chains, blocks, and anchors. In the mouths of harbors the same effect is produced, but in a somewhat different way. Here, as a general rule, there is little or no current at the bottom of the channel. But during every storm there is a heavy undertow, which will perform the same service as the current in the river. This undertow only needs to be broken up into eddies and cross-currents to cut into and wash away the bar; which it will do with a rapidity hardly to be believed by one who has never witnessed the operation. The same result may be produced on bars where no channel previously existed; and thus new harbors may be opened whenever there is an inner body of water deep enough for shipping, with a bar across the entrance.

The advantages of this invention are great and manifest. In nearly all our harbors, both on the lakes and on the seaboard, the formation of bars in the channel is a great, a constantly renewed, and constantly increasing evil. The expense of removing these bars in the ordinary way, by dredging, is immense; and yet they must be removed or the trade and commerce of our lake and seaboard towns and cities will be seriously injured, or even wholly lost. The same is true, though to a less extent, with many of our rivers. Any cheap and effectual way of removing the bars by which their navigation is impeded would be a national blessing, and this way I think I have invented.

In describing my invention above it will be seen that I have confined myself to one particular contrivance, viz, a chain or series of chains, with wooden blocks of a certain shape attached. I have done this, not with any view of limiting my claim to this particular device, but simply because that is the form and arrangement which I deem, on the whole, best fitted to answer the intended purpose. It is obvious, however, that many modifications of this plan may be adopted without departing from the principle of my invention. Thus, instead of a chain, a timber or timbers, or even a stout rope, may be used to support the blocks; or each block may be kept in place by being attached to an anchor, made as above explained; or, instead of using blocks of wood, and of the particular shape shown in the drawings, other blocks, made of iron and hollow, or of any other suitable material, and of a great variety of shapes, may be substituted. None of these details of construction are deemed material. All that is essential is, that there should be a series of obstructions or agitators fixed in the bottom of the channel, to break the current and turn it against the bar, as above explained.

What I claim, then, as my invention, and desire to secure by Letters Patent, is—

The method of removing bars of sand, or mud, or gravel, in the beds of rivers, or at the mouths of ports and harbors, or similar places, by placing obstructions or agitators upon said bars, for the purpose of breaking up the current, and thereby causing it to cut into and wash away the bar, all substantially as above shown.

In witness whereof I have hereto set my hand this 15th day of December, one thousand eight hundred and sixty-five.

SYDNEY S. DURFEE.
